CLAIM

The ornamental design for a can, as shown and described.

DESCRIPTION

FIG. 1 is a top perspective view of a can showing our new design;

FIG. 2 is a side elevational view thereof, the side opposite being a mirror image of the side shown;

FIG. 3 is a top plan view thereof;

FIG. 4 is a bottom plan view thereof; and,

FIG. 5 is a cross sectional view taken on line 5—5 of FIG. 2.

The characteristic feature of our design resides in the specific configuration of the fluting pattern in combination with the can.
